UNITED STATES PATENT OFFICE.

PETER E. SHIRK, OF BLUE BALL, PENNSYLVANIA.

MEAT-CHOPPING MACHINE.

SPECIFICATION forming part of Letters Patent No. 339,222, dated April 6, 1886.

Application filed October 22, 1884. Renewed February 9, 1886. Serial No. 191,383. (No model.)

To all whom it may concern:

Be it known that I, PETER E. SHIRK, of Blue Ball, in the county of Lancaster and State of Pennsylvania, have invented certain

5 Improvements in Meat-Chopping Machines, of which the following is a specification.

This invention relates to that class of chopping-machines in which the rotary chopping-block is used in connection with a series of 10 rising and falling knives actuated by cams; and it consists in various minor considerations hereinafter described and claimed.

Figure 1 represents a top plan view of my machine. Fig. 2 is a longitudinal and vertical section of the same on the line $x x$. Fig. 15 3 is a plan view of the spring-arms and connections for depressing the knives. Fig. 4 is a bottom plan view of the chopping-block and its driving-gear.

20 Referring to the accompanying drawings, A represents a flat bed or table provided, if desired, with lugs or otherwise, also provided at one end with upright standards a , and near the opposite end with an upright post or pivot, 25 b , also with rollers c , to support the chopping-block B , which is seated thereon, as shown, to revolve about the pivot b . Beneath the block there is seated a worm-wheel, C , sustained independently of the block by the central pivot, and arranged to engage with studs or pins projecting downward from the block 30 for the purpose of imparting motion thereto. This worm-wheel engages with and is driven by a worm, D , on one end of a horizontal shaft, E , which is seated in bearings on the frame and provided at the outer end with a sprocket-wheel, F .

In suitable bearings on the standard a , I 35 mount a horizontal driving-shaft, G , provided at one end with a sprocket-wheel, H , from which motion is transmitted through a chain, I , to the sprocket-wheel F , to effect the rotation of the chopping-block.

To a cross-bar or plate, I' , which is secured 40 to the upper ends of the standards a , I pivot a series of horizontal parallel arms, J , each of which is provided at its distal end with an adjustable knife, K . The arms are provided on the under side with shoulders d , acting on 45 cams L , secured on the driving-shaft G , as shown in the drawings, the arrangement be-

ing such that as the shaft is rotated the cams will lift and release the arms in succession, thereby raising the knives and permitting them to fall upon the block.

55

In order that the knives may be caused to act with more or less force, as required, I connect each arm J by a cord, M , with an elastic arm or spring, N , located beneath the table. The series of springs N are secured at one end 60 of a horizontal rock-shaft, O , provided with a rigid hand-lever, P , which engages at one end with a rack-bar, Q . By depressing this lever the tension of the springs N and the force of the knives may be modified.

65

For the purpose of securing uniformity of motion I propose to provide a second shaft, R , bearing at one end a fly-wheel, S , and at the opposite end a pinion, T , engaging with a large spur-wheel, U , on the main shaft. By 70 moving the shaft R or its pinion endwise the fly-wheel may be disconnected.

75

It will be observed that under my construction the chopping-block is adapted for removal independently of the worm-wheel. 75 This is important in that it avoids the difficulties which are commonly encountered when the gear-wheel is attached to the block and removed therewith, and prevents disagreeable contact by the operator with the lubricating material, with which the gear is usually covered.

80

I am aware that knife-arms lifted by cams have been connected by spiral springs to a rod adjustable by a hand-lever, and this I do 85 not claim.

My construction is advantageous because of its extreme simplicity, and because it permits the use of long and highly elastic springs.

Having thus described my machine, what I 90 claim is—

1. In a meat-chopper, the pivoted knife-carrying arms J and their lifting-cams L , in combination with a transverse rock-shaft, O , a series of elastic arms or springs, N , secured to 95 said shaft, cords or like connections extended from their respective springs to the knife-arms, the lever P , secured to the rock-shaft, and the locking device for said lever.

2. In a meat-chopping machine, the combination of the fixed upright pivot b , the series 100 of rollers c , the worm-wheel encircling the

pivot and sustained upon the rollers, the worm and the removable chopping-block seated upon the worm-wheel, and provided with the central hole to receive the pivot and with the 5 stud to engage the wheel, as described and shown.

In testimony whereof I hereunto set my

hand this 1st day of October, 1884, in the presence of two attesting witnesses.

PETER E. SHIRK.
